FOLDABLE EYESHADE

Glen A. Lougee, Laconia, N. H.

Application October 19, 1956, Serial No. 617,121

2 Claims. (Cl. 2—12)

This invention relates to an improved foldable eyeshade. The primary object of the invention is to provide a more efficient and practical eyeshade, made of flat or sheet material, wherein temple pieces are hinged to a forehead engaging panel to be folded against the back of the panel in a flat and compact condition, the axes of the hinge means being on the bias with respect to the panel and the temple pieces so as to render the temple pieces relatively resiliently associated with the forehead engaging panel and resist excessively free hinging of the temple pieces relative to the panel and provide for more secure mounting of the eyeshade in place on the head of a wearer.

Another object of the invention is to provide an eyeshade of the character indicated, which can be made in attractive, rugged, and serviceable forms at relatively low cost, is easily used, and is highly practical, serviceable and acceptable for the purpose intended.

These together with other objects and advantages which will become apparent reside in the details of construction and operation as more fully hereinafter described and claimed, reference being had to the accompanying drawings forming a part hereof, wherein like numerals refer to like parts throughout the several views, and in which:

Figure 1 is a perspective view of an eyeshade in accordance with the present invention, disposed on a wearer's head;

Figure 2 is an enlarged top plan view of the eyeshade;

Figure 3 is a vertical longitudinal sectional view taken substantially on line 3—3 of Figure 2;

Figure 4 is a rear elevational view of the eyeshade in folded position;

Figure 5 is a side elevation of the eyeshade in folded condition; and

Figure 6 is a vertical sectional view taken substantially on line 6—6 of Figure 4.

Referring to the drawings in detail, the illustrated eyeshade 10 comprises transversely elongated convex-concave forwardly bowed panel 12 of any suitable material such as plastic, cardboard, and the like, for engaging across the forehead 14 of the head W of a wearer. The panel 12 has a slightly longitudinally curved upper edge 16, and a more greatly longitudinally curved lower edge 18, the lower edge 18 having a greater radius of curvature than the upper edge 16, so that when the upper edge 16 is engaged with the forehead 14 of a wearer, the lower edge 18 extends forwardly and downwardly, in shading relationship to the eyes of the wearer. The opposite ends 20 and 22 of the main panel 12 flare outwardly and downwardly, on a bias, from the upper edge 16 to the lower edge 18.

Pivottally connected to the straight ends 20 and 22 of the panel 12 are right and left temple pieces indicated generally at 24 and 26, respectively. The temple pieces comprise convex-concave segmental panels 28 and 30, respectively, having rearwardly and upwardly curved lower edges 32 and 34, respectively, and slightly curved upper edges 36 and 38, respectively, having the same radius

2

of curvature as the upper edge 16 of the panel 12 and being continuations of the upper edge 16 of the panel 12.

The panels 28 and 30 have forward ends 40 and 44, which are on a bias, and which extend forwardly and downwardly and are of the same length as the ends 20 and 22 of the panel 12. The ends 20 and 22 of the panel 12 and the ends 40 and 44 of the panels 28 and 30 have thereon interengaged lugs 21 and 23, respectively, which are traversed by hinge pins 48 and 50, respectively, whereby the temple pieces are hinged on a bias to the main panel 12, to be disposed in the unfolded position shown in Figure 2, or folded to the position shown in Figure 4.

The temple piece panels 28 and 30 have rearwardly declining rear ends 46, which are on a bias, and which merge into the forward ends of rearwardly tapering, flat temples 52 and 54, respectively. The temples have upper edges 55 and 57 which are in continuation with the upper edges 36 and 38 of the temple panels 28 and 30, and lower edges 53 which curve upwardly and rearwardly. The rear ends of the temples 52 and 54 merge into rearwardly and downwardly and forwardly curved ear hooks 56 and 58.

The foregoing is considered to be illustrative only of the principles of the invention. Since numerous modifications and changes will readily occur to those skilled in the art, it is not desired to limit the invention to the exact construction and operation shown and described, and accordingly all suitable modifications and equivalents may be resorted to, as fall within the scope of the appended claims.

What is claimed as new is as follows:

1. In an eyeshade, a transversely and forwardly curved and elongated main panel having upper and lower edges, said upper edge being slightly concavely curved forehead engaging edge and said lower edge being convexly curved, the upper edge having a greater radius of curvature than said lower edge, said main panel having beveled edges which diverge from each other downwardly and forwardly, temple pieces comprising segmental temple panels having mutually downwardly divergent forward and rear vertical end edges said forward end edges extending forwardly and downwardly and said rear end edges extending rearwardly and downwardly relative to the vertical, the forward end edges of the temple panels being coextensive with the end edges of the main panel, hinge means connecting together the forward end edges of the temple panels and the end edges of the main panel whereby the temple pieces are hinged on a bias relative to the main panel, said temple panels being longitudinally and laterally outwardly curved between their end edges, the rear end edges of the temple panels being shorter than their forward end edges, and straight flat rearwardly tapering temples having forward ends merged into the rear end edges of the temple panels, the temples being laterally inset relative to the temple panels, and ear hooks on the rear ends of the temples.

2. In an eye shade having a transversely elongated and forwardly curved main panel having beveled end edges which diverge relative to each other in forward and downward directions, longitudinally and laterally outwardly curved temple panels having downwardly divergent forward and rear vertical end edges, the forward end edges of the temple panels being co-extensive with and hinged to the end edges of the main panel, the rear end edges of the temple panels being shorter than said forward end edges, and straight flat temples having forward ends secured to the rear end edges of the temple panels, the temples being relatively narrow and being laterally inwardly inset relative to the temple panels.
